UNITED STATES PATENT OFFICE.

HENRY P. VOTH AND EDWARD SIEBRASSE, OF FEATHERSTONE TOWNSHIP, GOODHUE COUNTY, MINNESOTA.

ATTACHMENT TO THE CAPS OF WIND-STACKERS OF THRESHING-MACHINES.

No. 887,360.

Specification of Letters Patent.

Patented May 12, 1908.

Application filed February 26, 1908. Serial No. 417,943.

To all whom it may concern:

Be it known that we, HENRY P. VOTH and EDWARD SIEBRASSE, each of whom is a citizen of the United States, and each of whom resides in the township of Featherstone, in the county of Goodhue and State of Minnesota, have invented a new and useful Invention in Attachments to the Caps of Wind-Stackers of Threshing-Machines, of which the following is a specification.

Our invention relates to the separation of dust, rust and dirt from straw in stacking of same, and improved facility in stacking the straw which will be explained herein. We attain this object by the mechanism which will be illustrated in the accompanying drawing in which—

Figure 1 shows our device attached to cap of threshing machine as in use in connection therewith. Fig. 2 is a view showing how the device is attached to the cap. Fig. 3 shows a section of the three different parts which in combination with the cap of the stacker tube constitute our invention.

Similar letters refer to similar parts throughout the several views.

There is no wood about our invention as all the parts are galvanized steel.

In Fig. 3 the lower drawing *f* is a section of the inner band which is about $1\frac{1}{2}$ inches wide $\#16$ gage, bent in a semicircle to correspond to the outside of the lower part of the cap of the stacker tube. The distance across from end to end is about 18 inches, and on said band *f* is a crimp or fold *a* that is bent forwards as shown in Fig. 3. The part *g* shown in Fig. 3 is a section of the outer band which is about 1 inch in width, bent in a semi circle to correspond with and fit over the inner band *f*, and *d* on said band *g* is one of a series of flutings on the inner side of said band *g* into which a series of steel wires *e* are placed, which wires are bent in form shown in Fig. 3. There are the same number of flutings in said outer band *g* corresponding to the number of wires *e* to be fitted therein. And *e* above mentioned is one of the several wires shown in Fig. 3 and bent in form shown therein. Each of said wires is not quite $\frac{3}{16}$ of an inch thick. There are about 26 wires, each wire being about 10 inches in length, comprising a series of 13 pairs bent in form shown in

Fig. 3, and said 26 wires are an inch apart. These wires *e* are placed in flutings *d*, the tops of the wires extending over tops of 55 the flutings in band *g* preventing them from slipping downwards, and the upper part or bend of each set of said wires rests against the crimp or fold *a* shown on inner band *f*, and thereby prevented from slipping upwards. 60 Band *g* is placed on the outside of band *f* below fold or crimp *a*, the wires *e* are fitted into flutings on the inside of band *g*, the bend or top of wires *e* extending over the top of the flutings and resting against fold or crimp 65 *a* of said band *g*, the bands are riveted together, *b* showing a series of rivet holes for that purpose, and this device so riveted together, is attached to the cap of the stacker tube by bolts *c* shown in Fig. 2. 70

The following explanation is necessary in order that the usefulness of our invention may be understood. In stacking straw, the windstacker without our attachment to the hood or cap, does not separate dust rust and dirt from the straw, as the dust rust and dirt is blown together with the straw. The straw flies around so that one in stacking the straw cannot get close to the cap of the stacker tube and stack to advantage. 80

With our attachment, the straw in leaving the stacker tube is blown against these wires *e*, and by its weight falls leaving an opening between each wire and the dust, rust dirt, and small particles of chaff escape with the wind, and thus the straw may be stacked free from dust, rust dirt and small particles of chaff, and in stacking the straw, one can get close to the cap of the stacker tube, and thus stack to great advantage. 90

What we claim as our invention, and desire to secure by Letters Patent is,

In combination with the cap, of a stacker tube, the inner band *f*, with fold or crimp *a*; the outer band *g*, provided with the flutings *d*, with wires *e*, fitted into said flutings *d*, said bands *f* and *g* riveted together, as described, and attached to the lower part of the cap of the stacker tube substantially as described, 95

HENRY P. VOTH.
EDWARD SIEBRASSE
